UNITED STATES PATENT OFFICE.

EDWARD CLIFF, OF NEWARK, NEW JERSEY, ASSIGNOR TO THE CLIFF & GUIBERT COMPANY, OF NEW YORK, N. Y.

DESIGN FOR A SIDE FRAME FOR HOSE-BRACKETS.

SPECIFICATION forming part of Design No. 33,172, dated September 4, 1900.

Application filed July 20, 1900. Serial No. 24,341. Term of patent 14 years.

To all whom it may concern:

Be it known that I, EDWARD CLIFF, a citizen of the United States, residing at Newark, in the county of Essex and State of New Jersey, have invented and produced a new and original Design for a Side Frame for Hose-Brackets, of which the following is a specification, reference being had to the accompanying drawings, forming a part thereof, and in which—

Figure 1 is a top view of a side frame bearing and incorporating my design. Fig. 2 is a side elevation looking at the outer face or side of same, and Fig. 3 is a like view looking at the inner face or side of same.

The leading feature of my design consists in the form and configuration of the side frame, substantially as shown in the drawings.

In the drawings, A designates the side frame, which is elongated in a horizontal direction, as shown, said side frame being greater in length than in height. The side frame A is also of the skeleton form shown, being composed of the connected parts B,

some of which define the horizontal series of openings which occupy the central horizontal field or portion of the side frame, and the other of which parts B represent horizontal rows of individual vertical bars extending upward and downward, respectively, to the upper and lower horizontal edges of said side frame. The parts B of the skeleton side frame A all present a harmonious outline or finish, in that the outer side surfaces of all of said parts B are substantially smooth and convex, whereby said parts have the appearance of being strongly in relief and the side frame as a whole is rendered attractive and distinctive in appearance.

What I claim is—

The design for a side frame for hose-brackets, substantially as shown and described.

Signed at New York, in the county and State of New York, this 19th day of July, 1900.

EDWARD CLIFF.
